UNITED STATES PATENT OFFICE.

GEORGE HILPERT, OF PARKERSBURG, WEST VIRGINIA.

DESIGN FOR A GAME-BOARD.

SPECIFICATION forming part of Design No. 35,014, dated August 27, 1901.

Application filed July 16, 1901. Serial No. 68,549. Term of patent 7 years.

To all whom it may concern:

Be it known that I, GEORGE HILPERT, a citizen of the United States, residing at Parkersburg, in the county of Wood and State of West Virginia, have invented and produced an original and new Design for a Game-Board, of which the following is a specification, reference being had to the accompanying drawings, forming a part thereof.

10 In the drawings, Figure 1 shows the invention in side elevation, and Fig. 2 illustrates the same in plan view.

As shown in the figures, the essential feature of my design consists of a table having a plain 15 flat circular top A, supported upon three equidistant-spaced legs a, said top having a plurality of equidistant-spaced pins b extending vertically from the top thereof, said pins being arranged in a circle concentric with and

in close juxtaposition to the periphery of the 20 table-top. Each pin b, as shown, tapers upwardly from its base and is surmounted by a knob or bulbous-shaped head c. Arranged centrally of the table-top A is a vertical mast d, having a lower ornamental part and an 25 upper plane portion extending far above the top of the pins b.

I claim as my invention—

The design for a game-board herein shown and described. 30

In testimony whereof I have signed my name to this specification in the presence of two subscribing witnesses.

GEORGE HILPERT.
